UNITED STATES PATENT OFFICE

HUGH J. BAKER, OF INDIANAPOLIS, INDIANA

ADJUSTABLE SHORE

Application filed September 8, 1927. Serial No. 218,336.

My invention is concerned with shores or adjustable braces of the kind frequently employed to support the forms used in poured concrete building construction. It is the object of my invention to produce an adjustable shore which, while light in weight, will be strong enough to sustain the loads to which it is subjected in use. A further object of my invention is to produce a shore in which the locking device, which holds the shore extended against the sustained load, will be simple in construction and positive in operation. A still further object of my invention is to produce a shore of the type described which will be durable.

I accomplish the above objects by constructing my shore of inner and outer telescoping parts, the inner part preferably being a rectangular timber and the outer part conveniently being formed of four longitudinally extending pieces of angle iron or other suitable structural shapes interconnected and disposed at the corners of the inner member to form a hollow base within which the inner member is longitudinally slidable. Movable with one of these shore parts, desirably the inner shore part, I provide one or more dogs which co-operate with the corner members forming the outer short part to hold the shore extended against the load which it sustains.

The accompanying drawings illustrate my invention: Fig. 1 is a fragmental longitudinal section through a shore embodying my invention; Fig. 2 is another longitudinal section on the line 2—2 of Fig. 1; Figs. 3 and 4 are transverse sections respectively on the lines 3—3 and 4—4 of Fig. 1; Fig. 5 is a perspective view of the movable cross brace which is embodied in the construction illustrated in Figs. 1 to 4 inclusive; Fig. 6 is a perspective view of the support for the dogs and movable cross brace; Fig. 7 is a longitudinal section on the line 7—7 of Fig. 8 showing a modification of my invention; Fig. 8 is a transverse section on the line 8—8 of Fig. 7; and Fig. 9 is a fragmental longitudinal section illustrating a further modification of my invention.

In the construction illustrated in the drawings, the shore comprises two telescoping

parts, an inner member 15 which may be conveniently a timber of rectangular cross section and an outer member desirably formed of four angle irons 16 which are disposed at the corners of the timber 15 and are rigidly interconnected and braced as by means of one or more straps 17. The four angles 16 form a hollow base within which the timber 15 is longitudinally slidable. Movable with the timber 15 in the base formed by the angles 16 is a dog support 18 having two depending ears 19 between which there extends a rod or shaft 20 adapted to carry a pair of dogs 21. These dogs 21 are desirably U-shaped as is evident from Fig. 4. The parallel legs of each of the U-shaped dogs terminate in sharp edges 22 adapted to engage the inner surface of the angles 16, while the intermediate leg 23 may serve as a counterweight tending to rotate the dog about the shaft 20 in a direction to cause engagement of the edges 22 with the inner faces of the angles 16.

Also connected to the dog support 18 is a movable cross tie 25 which is desirably mounted on the shaft or rod 20. This cross tie 25 extends transversely of the shore-base and projects outwardly beyond opposite pairs of the angles 16 where it is provided with transverse flanges 26 lying against the outer faces of those legs of the angle irons which are engaged by the dogs 21. These flanges 26, by reason of their engagement with the outer faces of the angles 16, prevent any outward bowing of such angles under the distorting influence caused by the outward pressure of the sharp edges 22 of the dogs.

Desirably, although not necessarily, the dog carrier or support 18 is not directly connected to the timber 15. Instead, I may connect the dog carrier 18 to the timber 15 through a means which will permit relative longitudinal movement of the timber and carrier 18, as the possibility of such movement will facilitate release of the dogs when it is desired to collapse the shore. To this end, I provide between the upper surface of the dog support 18 and bottom face of the timber 15 a pair of complementarily tapered wedges 28 as is clear from Fig. 1. If desired, these wedges may be provided with parallel

slots 29 through which there passes a link 30 which serves to interconnect the wedges without interfering with their relative movement. To connect the lower wedge 28 with the dog carrier 18, I may provide a screw 31 which extends into the lower face of the wedge 28 through a slot 32 in the dog carrier 18. Desirably, I provide the lower end of the timber 15 with a plate 33 which serves to protect it from injury. The lower face of the plate 33 and the upper face of the dog carrier 18 may be provided with spaced flanges 34 which serve as guides for the wedges 28.

For the purpose of adjustably extending the shore, I may provide the extending or raising mechanism illustrated in Fig. 1. This comprises a fulcrum piece 35 having a groove 36 adapted to receive within it a leg of one of the angles 16. The groove 36 is somewhat wider than the thickness of the angle flange which is received within it, thus permitting the part 35 to be tilted relative to the angle 16 to cause the ends of the side walls of the groove 36 to bite into the angle iron to prevent movement of the fulcrum piece 35 along the angle. To the fulcrum piece 35 is pivotally connected a raising lever 37, the shorter arm of which has mounted on it a thrust member 38 adapted to bear against downwardly projecting bosses 39 on the dogs 21.

In operation, the two wedges 28 are first placed approximately in the position illustrated in Fig. 1, and the shore is then extended to the desired length by the extending or raising means shown or by any other means. In the operation of the elevating means illustrated in Fig. 1, it will be evident that depressing the outer end of the lever 37 will cause an upward movement of the timber 15 together with all the locking mechanism. It is to be noted that in this operation the reaction at the fulcrum of the lever 37 tends to tilt the fulcrum piece 35 thus causing it to be locked to the angle 16 with which it is engaged. The thrust member 38 bearing on the lugs 39 tends to force the sharp edges 22 of the dogs 21 into engagement with the inner faces of the angle 16, thus insuring immediate locking of the dogs when the upward force exerted on them is released. When the shore is extended to the desired degree, the sharp edges 22 of the dogs are held in engagement with the inner faces of the angles, and any load which is applied to the upper end of the timber 15 increases the outward force with which the dogs bear against the angles.

When it is desired to collapse the shore, the two wedges 28 may be driven inwardly to permit the dog carrier 18 and dogs 21 to be raised without increasing the overall length of the shore. This raising of the dog carrier 18 facilitates disengagement of the sharp edges 22 of the dogs from the angles 16 and permits the shore to be readily collapsed.

The wedges 28 may be eliminated, the inner member 15 resting directly on the dog carrier 18. The shore may then be collapsed by tapping the upper end of the dogs with a hammer or other tool preferably on the intermediate leg 23.

In Figs. 7 and 8, I have shown a modification of my invention in which the dog carrier 18 and the wedges 28 are eliminated. In this device, the dogs 42 are pivotally mounted on a transverse shaft 43 carried by the movable cross brace 25. In the modification of my invention illustrated in Figs. 7 and 8, instead of providing a single pair of dogs, I provide two pairs which are mounted on opposite sides of the brace 25 as is clear from Fig. 8. The lower ends of these dogs bear against the inner faces of the angles 16 as do the corresponding edges of the dogs 21 shown in Figs. 1 to 4 inclusive. The upper ends of the dogs 42, instead of merely serving as counterweights, bear directly against the lower face of the timber 15, and the force exerted on the upper ends of the dogs by the timber 15 tends to rotate them about the shaft 43 to cause their lower edges to become engaged firmly with the angle 16, thus locking the shore in extended position.

In the further modification of my invention illustrated in Fig. 9, the lower end of the timber 15 has secured to it a dog carrier 50. The dog carrier 50 is provided with a downwardly extending lug 51 through which there extends a shaft 52 serving as a support for pairs of dogs 53, the edges of these dogs engaging the inner faces of the angle 16 similarly to the manner in which the dogs in previously described modifications operate. The cross brace 54 which I employ in this modification of my invention has the flanges 26 embodied in the cross braces heretofore described, but it differs from other cross braces in that it is connected to the dog carrier through a lost motion connection as by means of a slot 55 which receives the shaft 52. The cross brace 54 is also provided with laterally extending bosses 56 which bear against the lower faces of the dogs 53 and, when the brace 54 is raised, rotate the dogs 53 to cause them to engage the inner faces of the angles 16.

In the operation of the device illustrated in Fig. 9, the timber 15 is raised by pressure applied to the cross brace 54. As the cross brace moves upward relative to the dogs 53, which upward movement is provided for by reason of the slot 55, the bosses 56 engage the dogs 53 and force them into contact with the inner faces of the angles 16. Upon release of the raising force, the cross brace 54 drops downward to a position limited by the length of the slot 55, thus disengaging the bosses 56 from the dogs 53. This disengagement, however, does not effect the release of the dogs from the angles, for the downward force transmitted to the dogs from the

timber 15 tends to force the lower edges of the dogs outward into more firm engagement with the angles.

In all the modifications of my invention described it will be noted that the dogs are pivotally interconnected on an axis disposed above the level at which the edges of the dogs engage the angles. Thus the downward force which the timber 15 exerts on the dogs, either directly as in the modification of the invention shown in Figs. 7 and 8 or indirectly as in the other modifications, tends to spread the lower edges of the dogs apart thus increasing the pressure which they exert on the faces of the angles 6. This pressure never operates to spread the angles 16 apart, for any tendency of such angles to spread is opposed by the flanges 26 of the cross tie 25.

I claim as my invention:

1. An adjustable shore, comprising an inner shore-part, a hollow base within which said inner shore-part is slidable, said base including longitudinally extending structural members disposed at the corners of said inner shore-part to serve as guides therefor, a member movable longitudinally of said base, said member extending transversely of said base and projecting outward between the structural members on opposite sides of said base, and one or more pairs of locking dogs pivotally attached to said movable member within said base and adapted to have their free ends bear against the inner surfaces of said structural members, said movable member being provided with flanges lying against the outer surfaces of said structural members opposite the free ends of said dogs.

2. An adjustable shore, comprising an inner shore-part, a hollow base within which said inner shore-part is slidable, said base including longitudinally extending structural members disposed at the corners of said inner shore-part to serve as guides therefor, a member movable longitudinally of said base, and one or more pairs of locking dogs pivotally attached to said movable member within said base and adapted to have their free ends bear against the inner surfaces of said structural members.

3. An adjustable shore, comprising inner and outer telescoping parts, means for locking said parts in extended relation, said means including one or more pairs of pivotally mounted dogs, the free ends of said dogs being sharp-edged and adapted to engage inner surfaces of said outer part, each of said dogs being disposed so that a line through its edge and its axis of pivotal mounting makes with the shore axis an angle greater than 45°, and means tending to move said dogs to cause engagement of their free ends with the inner surfaces of said outer shore-part.

4. An adjustable shore, comprising a base, a part longitudinally slidable in said base, said base being provided with two spaced lon-

gitudinally extending flanges, means for locking said base and said part in extended relation, said locking means including one or more pairs of dogs pivotally mounted between said flanges, the free ends of said dogs being adapted to engage said flanges and to exert an outward pressure thereon, and means tending to move said dogs to cause engagement of their free ends with said flanges. 79

5. An adjustable shore, comprising a base, a part longitudinally slidable in said base, said base being provided with two spaced longitudinally extending flanges, means for locking said base and said part in extended relation, said locking means including one or more pairs of dogs pivotally mounted between said flanges, the free ends of said dogs being adapted to engage said flange and to exert an outward pressure thereon, and means longitudinally movable with said dogs 85 for co-operating with said flanges to prevent their separation under the forces exerted by said dogs.

6. An adjustable shore, comprising a base, a part longitudinally slidable in said base, said base being provided with two spaced longitudinally extending flanges, means for locking said base and said part in extended relation, said locking means including a member slidable longitudinally of said base, and one or more pairs of dogs pivotally mounted on said member between said flanges, the free ends of said dogs being adapted to engage said flanges and to exert an outward pressure thereon, said member having portions adapted to bear against the outer surfaces of said flanges to prevent their separation under the forces exerted by said dogs. 100

7. An adjustable shore, comprising a base, a part longitudinally slidable in said base, said base being provided with two spaced longitudinally extending flanges, means for locking said base and said part in extended relation, said locking means including one or more pairs of pivotally mounted dogs, the free ends of said dogs being adapted to engage said flanges and to exert an outward pressure thereon, and means tending to move said dogs to cause engagement of their free ends with said flanges. 105

8. An adjustable shore, comprising two parts movable longitudinally relative to each other, one of said parts being provided with a longitudinally extending flange, a member movable with the other of such parts, and a pivotally mounted locking dog longitudinally movable with said member and having a free end adapted to engage one side of said flange to hold the shore-parts extended, said member having a portion bearing against the opposite side of said flange to prevent distortion thereof under the force exerted on said flange by said dog. 120

9. An adjustable shore, comprising an in-

ner shore-part, a hollow base within which said inner shore-parts is slidable, said base including longitudinally extending angle irons disposed at the corners of said inner shore-part to serve as guides therefor, two locking dogs longitudinally movable with said inner shore-part and pivotally mounted whereby their free ends may engage the inner surfaces of opposite angle irons, and means longitudinally movable with said dogs for preventing separation of said angle irons.

10. An adjustable shore, comprising an inner shore part, a hollow base within which said inner shore-part is vertically slidable, and means for locking said inner shore part in extended position in said base, said means including a horizontally disposed pivot pin, members pivotally mounted on said pivot pin, means tending to force the lower ends of said members outward, and means connecting said pivot to said inner shore part for movement therewith, whereby downward pressure on said inner shore part acting through said pivot pin will tend to force 25 the lower ends of said members apart.

11. An adjustable shore, comprising two parts movable longitudinally relative to each other, one of said parts being provided with a longitudinally extending flange, a member movable with the other of said parts and having a portion bearing against one side of said flange, and a movable member acting against the opposite side of said flange and exerting a clamping action thereon to hold 35 the two telescoping parts in extended relation.

In witness whereof, I have hereunto set my hand at Indianapolis, Indiana, this 6th day of September, A. D. one thousand nine hundred and twenty-seven.

HUGH J. BAKER.
